UNITED STATES PATENT OFFICE.

PERCY S. WARMAN, OF ROSELLE, NEW JERSEY.

MOLD FOR CONCRETE SHIPS.

1,308,565.

Specification of Letters Patent.

Patented July 1, 1919.

Application filed May 11, 1918. Serial No. 233,996.

To all whom it may concern:

Be it known that I, PERCY S. WARMAN, a citizen of the United States, residing in Roselle, in the county of Union and State of New Jersey, have invented certain new and useful Improvements in Molds for Concrete Ships, of which the following is a specification.

This invention relates to molds in general and more especially to molds for concrete ships, barges and the like.

Among the main objects of the present invention it is aimed to provide a mold that can be repeatedly used for the construction 15 of ships and the like.

Another object of the present invention is to provide a mold for concrete structures having sectional walls which may be built up as the work progresses and be inserted in 20 place and removed with the greatest facility.

Still another object of the invention is to provide a sectional mold for concrete structures in which the greatest part thereof may 25 be assembled without the use of a bolt or screw, to which end the several elements have tongue and slot connection with one another.

A still further object of the present invention is the provision of a sectional mold for 30 concrete structures, the sections of which admirably adapt themselves to produce any angle or inclination of wall construction desired.

It is a particular object of the present invention to provide a permanent base in which the launching ways are formed from which the ship may be launched sidewise, and on which the standards are mounted 40 having slots to receive the tongues of plate sections that coöperate with one another to produce a wall having any desired inclination, angle and surface desired according to the requirements and which standards and 45 sections may be inserted in place and again removed with the greatest facility.

It is still another object of the invention to provide a mold for concrete sea-going vessels, or the like, having a permanent base 50 and sectional walls, and reinforcing means that particularly coöperate with the opposing sectional walls of the present arrangement to assist in defining and forming the concrete walls to be molded.

These and other features, capabilities and advantages of the invention will appear

from the subjoined detail description of certain specific embodiments of my invention illustrated in the accompanying drawings in which—

Figure 1 is a fragmental transverse section of a concrete vessel made according to the present invention.

Fig. 1^a is a fragmental end elevation of the base of the mold.

Fig. 2 is a fragmental longitudinal section of the same.

Fig. 3 is a fragmental perspective of a portion of the mold with concrete filled therein.

Fig. 4 is another fragmental perspective of a portion of the mold without the concrete filling.

Fig. 5 is a perspective of one of the mold parts.

Fig. 6 is a fragmental view of a portion of the reinforcement.

Fig. 7 is a fragmental section showing the method of securing the mold boards to the standards.

Fig. 8 is a fragmental elevation showing the position of the deck relative to the inner mold walls.

In the embodiment illustrated, there is provided a permanent base or platform 10 constituting the base of the dry dock from which the ship is to be launched, having the launching beams 11, formed in guideways in the base 10 and extending transversely of the base so that the ship may be launched 85 sidewise. The base is provided with a raised border portion 40 on one longitudinal side fixed to said base and a second border portion 41 on the other longitudinal side removably secured thereto to facilitate sidewise launching of the ship.

The base is preferably provided with a plurality of recesses 42 to receive the outer standards so positioned as to generally skeletonize the shape of the mold, the location of the recesses being arranged according to the shape and size of the vessel to be constructed.

The standards are generally composed of a main body portion *a*, outwardly extending flanges *b* in which (see Figs. 1, 3 and 4), are formed slots *c* inclined downwardly and inwardly relative to the mold wall of which the standard is a part, with the mouths of the slots disposed in the outer edges of the flanges *b* to receive the fingers 16 of the mold boards or plates 17. The fingers 16 preferably, as

2
shown, have inner portions 18 extending at right angles to the plate 17 and outer portions 19 extending back upon the portions 18 from inclined intervening junctures 20 5 which substantially conform to the inclination of the slots *c* so that when the plates 17 are secured to the flanges *b*, their inner mold faces will be substantially flush with the inner mold faces of the standards. For 10 manipulating a plate 17, any suitable form of gripping means may be provided such as the notched plates 43 secured to the outer faces of the plates 17 to be engaged by the handles 44 of any suitable construction preferably such as those used with sad-irons and 15 the like.

The arrangement and inclination of the standards will depend entirely upon their location, thus the standards along the hull 20 of the vessel will be substantially vertical and straight, as shown, whereas those disposed at the stern and bow of the vessel will generally be inclined or bent to suit the requirements. For the outer straight walls 25 of the mold, there will preferably be provided, as shown in Fig. 1, intermediate narrow width standards 12 and wide standards 13, the standards 13 being provided to define the ends of the bulkheads. For the inner straight walls of the mold, intermediate standards 24, such as illustrated in Fig. 3, are preferably provided in which the body portions *a* are inwardly bulging relative to the ship itself and outwardly bulging relative to the wall of which the standards are 30 a part; and corner defining standards 25 to define the junctures between the bulkheads and a side wall of the vessel, which corner standards are distinguished from the standards 12 in that one of the flanges *b* comprises essentially a flange portion 26 extending at right angles to the main body portion *a* and an outer flange portion 27 extending from said flange portion 26 over 35 parallel to the body portion 27.

For forming the deck of the vessel, the transverse channel irons 28 are provided which preferably extend from one inner standard 24 or 25 to another inner standard 40 24 or 25 opposite thereto, and rest on the tops of such inner opposing standards, which channel irons 28 are provided with flanges *d* similar to the flanges *b* having inclined slots *e* for interlocking with the tongues of mold 45 plates or boards, such as the mold boards 17.

To form the bulwarks of the vessel, short standards 32 are provided which substantially form upper continuations of the inner standards with which they conform and are 50 in alignment, and are spaced from such inner standards a space equal to the thickness of the deck. For properly supporting the standards 24 and 25, the standards 12 and 13 are provided with supporting plates 29 55 at their upper ends to extend from beyond

the standards 24 and 25 and are provided with plates 30 that engage the ears 31 formed on the short standards 32 and the ears 33 on the standards 24 and 25.

In the use of the present mold, concrete 70 will be spread on the permanent base 10 to the required thickness, and the mold boards forming the mold side walls gradually built up to suit the requirements, as the concrete is filled therein, until the tops of the standards 24 and 25 have been reached, whereupon the concrete may be spread on the mold boards 17 and the channel irons 28 securing such mold boards in place, to form the deck of the vessel, and then the plates further 75 built up along the standards 12, 13 and short standards 32 and concrete filled in to form the bulwarks of the vessel. For forming the bulkhead of the vessel, standards similar to the standards 12 will be suspended 80 along the channel irons 28 supported on opposing standards 24, and mold boards similar to the mold boards 17 secured between them, as shown in Fig. 1, to form opposing walls which are connected to the 85 flanges 27.

For reinforcing the concrete and also facilitating to assist the standards 12, 13, 24 and 25 in defining and forming the side walls of the hull of the vessel, the elongated 90 rods 34 may be provided to preferably extend down any of the standards 12 or 13, then along the base 10 and across to an opposing standard 12 or 13 and up along such opposing standard. To facilitate in 100 spacing the vertical portions of the rods 34 from one another, the skeletonized reinforcing sections 35 corresponding to the plates 17 in dimension are mounted on opposing rods 34 as shown in Fig. 6, each having 105 loops 45 on one side disposed near its upper end and loops 46 on its other side disposed near its lower end so as to coöperate with adjacent sections and permit adjacent sections to be looped to the same rods in proper 110 alignment. Along the standards suspended from the channel irons 28, reinforcing rods are disposed and spaced from one another, and anchored to one another by similar 115 standardized reinforcing sections 35.

It is obvious that various changes and modifications may be made to the details of construction without departing from the general spirit of the invention.

I claim:

1. In a mold for concrete structures, the combination with standards skeletonizing the shape to be constructed, mold plates, outwardly extending flanges on said standards, and fingers on said mold plates secured to said flanges to anchor said plates to said standards and form the mold walls. 125
2. In a mold for concrete ships, the combination with standards skeletonizing the shape of the ship to be constructed, mold 130

- plates, outward extending flanges on said standards, there being slots in said flanges, and fingers on said mold plates coöoperating with said slots to anchor said plates to said supports and form the mold walls.
3. In a mold for concrete structures, the combination with a permanent base, standards removably secured to said base, mold plates, outwardly extending flanges on said standards, and fingers on said mold plates removably secured to said flanges.
4. In a mold for concrete ships, the combination with metal standards, outwardly extending flanges on said standards, there being downwardly and inwardly inclining slots in said flanges having their mouths disposed in the outer edges of the flanges, and mold plates, fingers on said mold plates having outwardly extending portions, inclined portions at the ends of said outwardly extending portions corresponding to the inclined slots and engaging the same to anchor the plates to said standards.
5. In a mold for concrete ships, the combination with mold standards, outwardly extending flanges on said standards, there being inclined slots in said flanges having their mouths disposed in the outer edges of the flanges, and mold plates having outwardly extending portions, portions extending back on said outwardly extending portions, and intervening inclined junctures between said portions corresponding to the inclination of said slots and engaging the same to anchor the plates to said standards.
6. In a mold for concrete ships, the combination with metal standards, there being slots in said standards, mold plates, fingers on said mold plates engaging said slots to anchor the same thereto, and outwardly inclining upper ends on said mold plates to form seats for the lower edges of the adjacent upper mold plates.
7. In a mold for concrete ships, the combination with metal standards, skeletonizing the outer wall of a ship mold, inner metal standards, supporting plates extending from said outer standards from which said inner standards are suspended, and metal plates removably anchored to said standards to form the mold walls.
8. In a mold for concrete ships, the combination with a permanent base, outer standards removably secured to said base skeletonizing the outer wall of a ship mold, inner standards skeletonizing the inner wall of the ship mold, supporting plates extending from said outer standards over said inner standards from which said inner standards are suspended, flanges on said standards extending outwardly from the wall to be formed, there being inwardly and downwardly inclined slots in said flanges with their mouths in the outer edges of said flanges, mold plates, fingers on said mold plates having outwardly extending portions, portions extending back on said outwardly extending portions, and intervening junctures between said portions correspondingly inclined to the inclination of said slots and engaging the same to anchor the plates to said standards.
9. In a mold for concrete ships, the combination with a permanent base, outer standards removably secured to said base skeletonizing the outer wall of a ship mold, inner standards skeletonizing the inner wall of the ship mold, supporting plates extending from said outer standards over said inner standards from which said inner standards are suspended, flanges on said standards extending outward from the wall to be formed, inclined slots on said flanges, mold plates, fingers on said mold plates engaging said slots to anchor said plates to said standards and form the mold walls.
10. In a mold for concrete ships, the combination with a permanent base, outer standards removably secured to said base and skeletonizing the outer wall of a ship mold, inner standards skeletonizing the inner wall of the ship mold, supporting plates extending from said outer standards over said inner standards from which said inner standards are suspended, inclined slots in said standards, mold plates, and fingers on said mold plates having outwardly extending portions, portions extending back on said outwardly extending portions, and intervening inclined junctures between said portions corresponding to the inclination of said slots and engaging the same to anchor the plates to said standards.
11. In a mold for concrete ships, the combination with a permanent base, outer standards removably secured to said base and skeletonizing the outer wall of a ship mold, inner standards skeletonizing the inner wall of the ship mold, supporting plates extending from said outer standards over said inner standards from which said inner standards are suspended, flanges on said standards extending outwardly from the wall to be formed, there being inwardly and downwardly inclined slots in said flanges with their mouths in the outer edges of said flanges, mold plates, fingers on said mold plates having outwardly extending portions, portions extending back on said outwardly extending portions, and intervening junctures between said portions correspondingly inclined to the inclination of said slots and engaging the same to anchor the plates to said standards.
12. In a mold for concrete ships, the combination with a permanent base, having a raised border along one side fixed thereto, a raised border along the other side removably secured thereto, standards registering with said borders skeletonizing the shape of the ship to be molded and removably secured to said base, and mold plates removably secured to said standards to form the mold walls, the removably raised border

4
being provided to permit sidewise launching of the ship.

13. In a mold for concrete ships, the combination with a permanent base having recesses therein outlining the shape of the ship to be molded, outer standards removably secured in said recesses, inner standards suspended from said outer standards, and mold plates removably secured to said standards

10 to form the mold walls.

14. In a mold for concrete structures, the combination with standards skeletonizing the shape to be constructed, there being slots in said standards, mold plates, and

15 fingers on said mold plates coöperating with

said slots to removably anchor said plates to said standards.

15. In a mold for concrete structures, the combination with standards skeletonizing the shape to be constructed, outwardly extending flanges on said standards, there being slots in said flanges, mold plates, and fingers on said mold plates coöperating with said slots to removably anchor said plates to said standards. 20
